UNITED STATES PATENT OFFICE

164,641

REVOLVING PLAYING CARD DISPENSER

Elmer L. Jones, Los Angeles, Calif.

Application March 14, 1951, Serial No. 14,496

Term of patent 7 years

(Cl. D34—13)

To all whom it may concern:

Be it known that I, Elmer L. Jones, a citizen of the United States of America, residing at Los Angeles, county of Los Angeles, and State of California, have invented a new, original, and ornamental Design for a Revolving Playing Card Dispenser, of which the following is a specification, reference being had to the accompanying drawing, forming a part thereof, wherein:

I claim:

The ornamental design for a revolving playing card dispenser, as shown.

ELMER L. JONES.
